FIG.5.

੩੪

Charles E. Wines

Attorney

UNITED STATES PATENT OFFICE.

ALBERT L. MELVIN, OF DETROIT, MICHIGAN.

ANCHOR-POST.

1,347,865.

Specification of Letters Patent. Patented July 27, 1920.

Application filed November 26, 1915. Serial No. 63,381.

To all whom it may concern:

Be it known that I, ALBERT L. MELVIN, a citizen of the United States, residing at Detroit, county of Wayne, State of Michigan, have invented a certain new and useful Improvement in Anchor-Posts, and declare the following to be a full, clear, and exact description of the same, such as will enable others skilled in the art to which it pertains to make and use the same, reference being had to the accompanying drawings, which form a part of this specification.

This invention relates to anchor posts for use in supporting the framework of bill-boards, tanks, windmills and various other structures, and its object is a cheap and efficient device for the purpose that may be readily withdrawn from the ground. With the framework of bill-boards now ordinarily in use, the anchor posts are provided with a broad base and, if the superstructure is to be removed as is often required with bill-boards, it is quite expensive to excavate a sufficient area to secure the anchor posts and to leave the anchor posts in the ground is also an expense. With the device herein disclosed the post is adapted to be driven into the ground, thus not requiring excavation to place the post and the post is so constructed and arranged that after being driven it may be secured from removal by strain directly on the post itself by wind pressure or other force. The arrangement is such, however, that on proper manipulation of the locking device as herein disclosed, the post may be readily withdrawn for use in another location without the necessity of excavating. An object of the invention, therefore, is an anchor post adapted to be driven into the ground and provided with a means adapted to be set after the post is in place preventing removal of the post by force applied to the post and also adapted for ready removal by release of the setting means from the surface of the ground. These and other objects and the several novel features of the invention are hereinafter more fully described and claimed and shown in the accompanying drawings in which—

Figure 1 is a perspective view of a bill-board showing one of the anchor posts in position.

Fig. 2 is an enlarged side elevation of the post, the dotted lines showing the position

of the parts when set to prevent withdrawal of the post from the ground.

Fig. 3 is an elevation of the post taken at a right angle to that shown in Fig. 2. 60

Fig. 4 is a plan view of a driving head by means of which the post may be driven into the ground.

Fig. 5 is a vertical section of the head taken on line $x-x$ of Fig. 4. 65

Fig. 6 is a plan view of a plate used as a guide at the surface of the ground tending to hold the post in vertical position while being driven and preventing a "drift" of the post during the driving operation. 70

Similar characters refer to similar parts throughout the drawing and specification.

The post may be of any size required for use with the various structures to which it may be applied and preferably consists of 75 an angle-iron body member 1, one leg thereof being sharpened at the end 2, as shown particularly in Fig. 3, so that it may readily enter the ground. Slidably mounted on the inner angle of the body member 1 is the locking bar or member 3 also formed of angle-iron and preferably less in length than the body member 1. This member 3 is provided with a slot 4 or provided with holes in one of its legs and a bolt 5 passing 80 therethrough secured to the body member which prevents displacement of the locking bar relative to the body member. Pivoted mounted at 6 to the lower end 7 of the locking bar is a dog 8 having a shank extending through a slot 9 formed in one of the legs of the post as shown particularly in Figs. 1 and 2. The lower end 10 of the dog is pointed and is notched at 11 on the inner side thereof to engage over the end of the 95 unsharpened leg of the body 1 as shown particularly in Fig. 2. The end 10 of the dog being pointed as shown and one leg of the body being also pointed as at 2, the device may be readily driven into the ground. 100

After being so driven to position so that the upper end of the post projects slightly above the ground exposing the bolt holes 12 therein to which the superstructure may be secured, the locking bar 3 is then driven 105 downward. The slot 9 through which the shank of the dog 8 extends, as shown in Fig. 2, is of such length that the first downward movement of the dog is parallel with the side of the body member 1 until the notch 11 is out of engagement with the end of the body member. The shank of the dog 110

8 then engages the bottom end of the slot 9 and further downward movement of the locking bar 3 finally forces the dog 8 to assume the position shown by dotted lines in 5 Fig. 1, at a right angle to the anchor post and extending into the earth at the side thereof. With the parts in this last described position force applied to the post 1 to withdraw the same from the ground tends to 10 draw the dog upward through the ground at a right angle to the post. The dog 8 is made wider than the leg of the post as is indicated in Fig. 3, and thus great force 15 would be required to move the dog in such locked position as the withdrawing force applied to the post is applied to the dog at the lowermost point of the slot 9 as shown in Fig. 2, at one side of the pivot point and thus tends to draw the dog bodily upward 20 through the ground. As no ordinary pressure applied to the framework is sufficient to thus withdraw the post, the framework is securely held in position.

To readily withdraw the post from the 25 ground, it is first necessary to bring the dog to position parallel with the post. This may be accomplished by first pulling the locking bar 3 upward by any convenient instrument having an end adapted to engage 30 the aperture 13 in the upper end of the locking bar. The upward movement of the bar 3 draws the pivoted end of the dog upward until the shank thereof engages the upper 35 end of the notch 9 and further upward movement of the locking bar turns the dog on the pivot point 6 parallel to the post in position to be readily removed.

It is to be noted that the lower end 7 of 40 one leg of the locking bar is greater in length than the other leg which is provided with a blunt end 30. This end 30, upon driving the locking bar downward to force the dog into locking position, engages 45 against the shank of the dog as shown by dotted lines preventing further downward movement of the bar after the dog is forced to the locking position and preventing further upward movement of the dog about its pivot.

50 After the locking bar has been driven, the super-structure may be secured to the post by bolts passing through the holes 12 in the upper end thereof. After the superstructure and bolts are in place the locking bar 55 may no longer be moved upward relative to the body member and the locking device is thus held in locked position.

In order that the anchor post may be driven without injury to the driving end 60 thereof, I preferably employ a driving head 65 formed of any convenient material as metal, and in the lower end of this head is formed an angle shaped recess 16 fitting the angle-iron body member 1. When placed on the body member the end of the body

member engages a shoulder 18 in the head at the bottom of the angle shaped recess 16. After the post has been driven by use of the head, it is then necessary to drive the locking member 3, and for this purpose the 70 head is provided with an angle shaped hole 17 extending through the head and forming an enlargement of the recess 16 on the inner angle thereof. After the post has been driven an angle iron is inserted in this 75 angle shaped hole 17 engaging the end of the locking bar 3 and held in engagement therewith by this driving head. By driving the bar 3 the dog 8 is forced to locking 80 position as heretofore described.

In driving posts of the nature herein disclosed it is oftentimes a difficult matter to drive the post in vertical direction due to the nature of the ground, etc., and to prevent a "drift" of the post during the driving operation I provide a plate 19 having an L shaped opening 20 preferably centrally therein adapted to engage over the upper end of the post after it has been started slightly in the ground. This plate 90 is also provided with corner aperture 21, 21, etc., through which pins may be driven to hold the same in position on the surface of the ground. This plate tends to hold the upper end of the post from side wise movement during the driving operation and insures driving the post substantially vertically in the ground.

From the foregoing description it is evident that the post is simple in construction 100 and inexpensive, being formed of angle-iron parts and not requiring any machine work of a particular nature. The dog 3 may be formed of any desirable material, as malleable iron or other material not readily injured in the use to which the device is put and the device is readily insertible into the ground and locked from removal therefrom by force applied to the post itself.

Having thus briefly described my invention, what I claim and desire to secure by Letters Patent of the United States is—

1. An anchor post comprising a body member, a member adapted to engage over one end of the body member, providing a 115 driving point therefor, a bar slidably on the body member to which the driving point member is pivoted, and means whereby the said point is turned on its pivot to anchoring position by downward movement of the bar. 120

2. An anchor post comprising a body member, a member slidably mounted thereon, an anchoring device pivotally mounted to the slidable member, means for holding the anchoring device in position to form a 125 driving point for the said body during the driving thereof, and means whereby downward movement of the slidable member releases the anchoring device from driving position and forces it to anchoring position. 130

3. An anchor post comprising a body member adapted to be driven into the ground, a member relatively slidable thereon, and a dog or locking plate providing a driving point for the body member and having a shank extending through a slot provided in the body member and pivoted to the sliding member whereby said dog or plate may be forced to locking position by downward movement of the sliding member.
4. In combination an anchor post, a member having a hooked end normally engaging over the end of the post providing a driving point, a bar slidably mounted on the post to which the hooked member is pivotally mounted, downward movement of the bar releasing the point from engagement with the post and forcing it to anchoring position, a driving head for the post having a recess for the upper end of the post, and an aperture therein offset relative to the recess and in alignment with the end of the bar providing a guide for the insertion of a driving implement for the said bar.
5. An anchor post comprising an angle iron body member having a slot in one of its legs near the lower end thereof, a locking member slidable on the body member, and a dog or locking plate providing a driving point for the body member and having a shank extending through the slot in the body member and being pivoted to the sliding member, the arrangement being such that movement of the sliding member forces the dog or plate to a position at an angle to the body member, and that upward movement of the sliding member relative to the body member draws the dog or plate to the body member substantially as described.
6. An anchor post comprising a body member formed of angle iron and having a slot in one of the legs thereof near the lower end, the other of the legs having a sharp end, an angle iron locking bar slidably secured to the body, a dog pivotally mounted to the lower end of one of the legs of the locking bar having a shank extending through the slot in the body member and adapted to be engaged by the end of the other leg of the locking bar when forced to locking position, said dog having a sharp edge, and a slot at the rear of said sharp edge adapted to engage over the unsharpened leg of the body member when the locking bar is drawn to its uppermost position relative to the body member, said slot being of such length that downward movement of the locking bar relative to the body member first disengages the notched part of the dog from the said engaged leg, and further movement causes the shank to engage the bottom of the slot to turn the dog to practically a right angle with the body member substantially as described.

In testimony whereof I sign this specification.

ALBERT L. MELVIN.
